J. GRAY.
MERCHANTISE DISPLAY RACK.
APPLICATION FILED MAY 1, 1913.

1,078,728.

Patented Nov. 18, 1913.

UNITED STATES PATENT OFFICE.

JOHN GRAY, OF CENTRAL FALLS, RHODE ISLAND.

MERCHANDISE-DISPLAY RACK.

1,078,728.

Specification of Letters Patent. Patented Nov. 18, 1913.

Application filed May 1, 1913. Serial No. 764,844.

To all whom it may concern:

Be it known that I, JOHN GRAY, a citizen of the United States, residing at the city of Central Falls, in the county of Providence and State of Rhode Island, and whose post-office address is 15 Summer street, in said city, have invented certain new and useful Improvements in Merchandise-Display Racks, of which the following is a specification.

This invention relates to an attachment adapted to be mounted on a horizontally-arranged swinging arm and designed for advantageously displaying rugs, carpets, etc.

The objects in view are to provide two independent similarly sets of means carried by the arm, for raising and lowering to display a rug at each side thereof; a suspended bar to permit of attaching a rug thereto, from on the floor; hooks arranged for contacting with and supporting the bar at its uppermost position upon the rack, and means to simultaneously turn the hooks to release the bar in lowering the latter to the floor.

The invention consists in the features of construction and combination of parts hereinafter described and claimed.

In the accompanying sheet of drawings, Figure 1 is a side elevation of my improved rack, the rug supported thereby being shown in dotted lines. Fig. 2 is an enlarged detail transverse section of the rack, taken on line $x-x$ of Fig. 1, showing the normal opened positions of the hooks for supporting the rug-bar. Fig. 3 is a partial side elevation of the inner portion of the swinging arm, showing actuating means for operating to turn the supporting hooks to a closed position. Fig. 4 is a plan section taken on line $y-y$ of Fig. 3, showing a closed and an opened position which each hook assumes in its turning movement by the actuating means, and, Fig. 5 is an end view of the rack, at the outer part of its swinging arm.

My invention is applied for use on a T-shaped arm a which has one end pivotally connected to an inverted L-shaped piece b , secured to a wall or post c , and said arm being supported by a brace rod d from the outer portion of its central web and the lower end of said rod pivotally connected to a similarly-arranged angle piece b^1 on the wall or post. As I

apply two like sets of devices to the swinging arm a a description of one set will suffice to explain the construction and operation.

A series of equi-spaced blocks carrying pivotally-connected grooved rollers are mounted upon the top flange of the arm a , and each block e has its upper part forked, as at e^1 , to receive each roller, as f, f^2, f^3 , and its lower part designed to underlie the outer edge of said flange, as at e^2 . The rollers f, f^2, f^3 extend longitudinally of the arm and each opposed pair of blocks e is held in a fixed position transverse of the arm and between the underlying portion e^2 , by a clamping bolt g , in the manner shown in Fig. 2.

From the top flange of the arm a depend a series of hooks, and each hook member h has an enlarged head h^1 to rest upon the top face of said flange and its hook portion has a horizontal bottom, as h^2 , and the free portion inclined outwardly from the body or depending portion, as at h^3 .

A shaft i is journaled in hangers j, j^1 which are secured to the central web of the arm a , and each hanger has a supplementary bearing to receive the lower part of the body portion of each hook member h , as at points j^1, j^1 in Figs. 4 and 5.

At the inner part of the arm a and pivotally secured thereto is a bell-crank lever k , which has one free end connected to the end of the shaft i and its other end provided with an eye, as k^1 , for the attaching of a pull-wire connection l . An expanding coil spring m surrounds the shaft i and is interposed between a hanger j^2 , secured to the central web of the arm a , and a fixed collar n on said shaft. The shaft i is provided with longitudinally-arranged slotted openings, as at i^1 , to receive the bottom portions of the hook members h , in order to permit a turning movement to be given to said members by means of the pull-wire connection l . The action of the spring m tends to force the shaft i and keep the upper arm of its lever k against the top flange of the rack-arm a , in the manner shown in Fig. 3, thus said le-

ver forms a stop to limit the inward movement of said shaft, and at the same time the tension of said spring acts to keep the free portions of the hook members —*h*— inclined outwardly from the side of the arm —*a*—, to their opening positions shown in Figs. 1, 2 and 3.

A straight bar —*p*—, which is round in cross-section, has a series of small hooks —*q*— for attaching thereon a rug —*r*— to be displayed on the rack, and these hooks may be equi-spaced and secured in any suitable manner to said bar, as shown, or each hook may be bent to provide an eye to permit the latter to slide on said bar. On the rug-bar —*p*— are secured eye members —*s*— for attaching the ends of cables —*t*, *t*², *t*³— which, when the bar is in its lowermost position shown in Fig. 1, are each of a length to respectively pass within the grooves of the rollers —*f*, *f*², *f*³— and meet together, as at a point —*t*³— in Fig. 2, to form a short cable for attaching to a cleat —*u*— secured on the brace —*d*— of the rack. The cable —*t*— passes from the roller —*f*— direct to the inner groove, of a series of three, formed in the roller —*f*³—; the cable —*t*²— passes from the roller —*f*²— to the next outer groove of the roller —*f*³—; the cable —*t*³— passes around the outermost groove of the roller —*f*³—, and the said three cables converge to the uniting point of the single cable connection —*t*⁴—. As the bar —*p*— is lifted by the manually-operated cable connections to carry the rug from the floor level the said bar comes into contact with the inclined free portions —*h*³— of the hook members —*h*—, and the ends of the latter project outside of the plane of the grooves of the rollers —*f*, *f*²— and inner groove of the roller —*f*³—, as shown in Fig. 5, and thereby permit the said bar to enter within the hook portions of the members —*h*— and be supported by the same, in the manner shown at the left of Fig. 2. In the lowering operation the bar —*p*— is first elevated to clear from the hook portions of the members —*h*—, after which the wire connection —*l*— is pulled upon to actuate the shaft —*i*— to simultaneously turn said members —*h*—, to the closed position shown at the upper part of Fig. 4, when said bar —*p*— is then free to descend to a convenient location to permit detaching the rug therefrom.

Having a swinging rack-arm equipped with independent similarly-arranged devices, as described, enables to operate in raising a rug from the floor level, to a display position at each side of the rack, and at the same time facilitate in releasing the rug from its supporting point, in the operation of lowering to bring such article within easy reach for detachment.

What I claim as new and of my invention is—

1. In a merchandise display rack, in combination with a horizontal T-shaped swinging arm, a series of hooks carried by the top flange of said arm and having their free end portions inclined outwardly from the central web of the latter; a series of rollers carried by said arm, each roller provided with one or more grooves, and the inner grooves of said rollers being in a plane inwardly of the free ends of said hooks; a rug-supporting-bar having cable connections from the grooved rollers to operate in lifting said bar over the free ends of and within said hooks, and operating means carried by said arm to simultaneously turn the hooks and allow the said bar to descend to a lowermost position.

2. In a merchandise display rack, in combination with a horizontal T-shaped swinging arm, brackets arranged in pairs upon the top flange of said arm and each bracket carrying a grooved pulley; means to clamp each pair of brackets transverse of and to said arm; hook members journaled in the top flange of said arm and having their free portions bent to incline outwardly from the central web of said arm; independent rug-supporting-bars, each bar having cable connections from the pulleys of said brackets to operate in lifting either bar over the free ends of and within said hook members, and operating means carried at each side of said arm to simultaneously turn said hook members and allow either bar to descend to the floor level.

3. In a merchandise display rack, in combination with a horizontal T-shaped swinging arm, a series of equi-spaced grooved rollers carried by said arm; hook members loosely mounted in the top flange of said arm and having their free portions arranged to incline outwardly from the central web of the said arm; a slidable shaft carried at each side of said arm, each shaft having slotted openings to receive the bottoms of said hook members; a rug-supporting-bar having cable connections from the rollers to operate in lifting said bar to pass upon the inclines of the hook members and to enter the same; a bell crank lever mounted on said arm and having a pull-wire connection to operate in imparting an outer movement to said shaft in turning the hook members and allow the said bar to descend to the floor level.

Signed at Providence, R. I., this 30th day of April, 1913.

JOHN GRAY.
